WASH-OVER SPEAR MECHANISM

Cecil Ware, Greggton, Tex., assignor to Wash Overshot and Spear Engineers, Inc., Longview, Tex., a corporation of Texas

Filed June 29, 1956, Ser. No. 594,780

6 Claims. (Cl. 166—103)

This invention relates to fishing tools and more particularly to a pipe spear adapted for use within a wash-over pipe in the recovery of stuck pipe in wells, and especially in the recovery of pipe or drill collars which have become stuck in off bottom position in a well bore.

The invention finds particular utility in connection with the recovery of drill pipe, drill collars, or the like, which have become stuck in a well bore off bottom and which are broken off or have been uncoupled at a joint, the portion of the pipe below the break or uncoupled joint remaining in the bore. Under such conditions it is customary to wash-over and around the stuck portion of the pipe by the use of a wash-over pipe, the upper end of the stuck portion being engaged by a pipe spear, so that upon freeing of the stuck portion it will not fall to bottom and may be pulled out of the well bore, and may be removed from the wash-over pipe without performing a stripping operation.

The present invention has for an important object the provision of a pipe spear which is adapted for use within a wash-over pipe and including means whereby the spear may be grippingly engaged with the wash-over pipe for movement therewith, or may be released from the wash-over pipe to permit movement of the pipe over the spear, thus leaving the wash-over pipe to be moved up or down and rotated freely, but with the spear in a position to engage the wash-over pipe in the event that the fish should become unstuck and drop in the well bore.

A further object of the invention is to provide wash-over spear equipment, having slip mechanism by which the spear may be anchored in or released from the wash-over pipe and embodying slip holding means adapted to be affected by hydrostatic pressure in a well, upon downward movement of the fish in the well bore relative to the wash-over pipe.

Another object of the invention is to provide wash-over spear equipment having spear mechanism which is adapted to be supported in a wash-over pipe for rotation with the pipe, to engage the spear with a fish in a well and including means whereby the spear may be securely anchored to the wash-over pipe for release therefrom, as may be desired.

And another object of this invention is to provide a well tool adapted to be alternately anchored and releasably disposed in a pipe in a well bore which is precluded from an anchoring position by application of hydraulic pressure to flow a restriction member to maintain the anchoring means of the well tool in a static position.

Another object of the invention is to provide wash-over spear equipment including spear mechanism for engagement with a fish in a well and including mechanism for anchoring the spear to the wash-over pipe for rotation with the pipe, whereby the spear may be connected to the fish so that an upward pull may be exerted on the fish by pulling upwardly on the wash-over pipe, and which is releasable to permit independent movement of the wash-over pipe relative to the spear, whereby the wash-over

2

pipe may be removed leaving the spear attached to the fish.

The above and other important objects and advantages of the invention may best be understood from the following detailed explanation of the construction and mode of operation of the same when considered in conjunction with the annexed drawings, wherein—

Figures 1A and 1B are fragmentary side elevational views, partly in cross-section, illustrating a preferred embodiment of the invention and showing the parts latched in the released condition of the spear, Figure 1B being a downward extension of Figure 1A;

Figure 2 is a fragmentary view similar to that of Figure 1A, showing the spear anchoring mechanism of the invention unlatched and in anchoring position;

Figure 3 is a view similar to that of Figure 1A showing the spear anchoring mechanism unlatched and in releasing position or operating or reaming position; and

Figure 4 is a cross-sectional view taken along the line 4—4 of Figure 2, looking in the direction indicated by the arrows.

Referring now to the drawings in greater detail, the invention comprises a mandrel 12, having at its upper end suitable means for connecting the same to the lower end of a string of pipe, such as a tool joint, or the like, not shown, and provided at its lower end with suitable means, such as tool joint thread to engage the top of a fish, the invention also including spear mechanism of novel construction and arrangement to be anchored in the wash-over pipe 10 in position to be engaged with the upper end of a drill collar or pipe which is stuck in a well bore.

The spear mechanism (or unit) of the invention includes an inner tubular mandrel 12, whose upper end is formed with an external enlargement 14, which is internally threaded as indicated at 16, for the attachment thereto of any suitable type of grappling means, or by means of which an inner pipe may be connected in communication with the mandrel. The lower end of the mandrel 12 is externally threaded as indicated at 18, for the attachment thereto of an externally threaded pin element 20, adapted to be engaged with the upper end of a drill collar or pipe (not shown), whereby the spear (unit) is connected to such drill collar or pipe. Other suitable grappling means may, of course, be attached to the lower end of the spear (unit) to be engaged with well equipment stuck in the well bore.

The upper end of the pin element 20 forms an external upwardly facing shoulder 22, adjacent the lower end of the mandrel 12, for a purpose to be more fully pointed out hereinafter. A slip assembly surrounds the mandrel 12, comprising a tubular slip support 24, having a pin 30 therethrough, which works in a longitudinal slot 26 in the tubular mandrel 12, formed with a lateral branch slot 28 substantially mediate its ends, the pin being engageable in the branch slot 28 to hold the slip support element 24 against longitudinal movement on the mandrel, and being also movable out of the branch slot upon right hand rotation of the wash-over pipe relative to the slip assembly, to permit relative longitudinal movement of the mandrel 12 and assembly.

A number of upwardly tapering, externally toothed slips 32 are supported at their lower ends of the slip support 24. The slips are capable of lateral movement relative to the slip support into and out of gripping engagement with the surrounding wash-over pipe 10. The slips are supported on the support 24, by means of screws 34, extending through suitable openings 36 through the upper end portion of the slip 24, and provide sufficient clearance for the slips to be expanded into gripping engagement with the wash-over pipe 10, or retracted to positions out of engagement therewith. The slips are provided with external grooves 38, near their upper ends, within which

an annular spring element 40 is seated, in position to yieldingly urge the slip toward retracted position.

The slip support 24 has an externally reduced lower end portion 42, upon which an annular resilient element 44 is positioned, in surrounding relation to the support, and having cup-like upper and lower portions 46 and 48, respectively. The cups 46 and 48 are positioned for restricted flow engagement with the interior of the wash-over pipe, and which is also in restricted flow engagement with the exterior of the slip support. The restricted flow element 44 may be formed of any suitable material having the requisite properties, such as rubber, or the like, but not limited thereto, and may be provided with a medial ring 50, which seats upon the reduced lower end portion 42 of the support 24. The ring 50 is formed with a plurality of spaced openings, such as that indicated at 52, through which the material of the sealing element is molded. The ring 50 is retained in position on the slip support 24 by means of a sleeve 54, surrounding the support 24, and whose lower end is engageable with a nut 56, threaded upon the lower end of the support 24.

Beneath the slip assembly a friction block assembly is provided on the mandrel, which comprises a tubular cage 64, surrounding the mandrel and which is formed with externally opening recesses 66, within which friction shoes 68 are positioned for radial movement relative to the mandrel. Each of the friction shoes 68 are urged radially outwardly into frictional contact with the interior of the wash-over pipe 10 by suitable means, such as the coil spring 70. On the upper end of tubular cage 64 is cut a buttress thread 57 somewhat smaller than the outside diameter of the cage 64, which threads are to receive the yieldable portion 61 on the nut 56.

This nut 56 has on its lower end an extended portion provided with an internal buttress thread 57 which is engageable with an external thread 59, shown in Figure 1B, on the tubular cage 64. The nut 56 is slotted longitudinally to provide a plurality of fingers 61, to make this portion of nut 56 expansible, so that upon upward movement of wash-over pipe 10, tubular cage 64 will move upwardly to move the upper end of the cage into the nut 56 to engage the nut thread 57 with the cage thread 59 and releasably connect the friction dog cage 64 with the lower end of slip support 24, thus assuring sufficient friction to cause pin 30 to be moved in slot 26. By rotation of the wash-over pipe the friction cage 64 may be rotated therewith through the contact of the friction shoes 68 with the interior of the wash-over pipe to unscrew the thread 59 from the thread 57 to release the slip support 24 from the tubular cage 64.

The slips 32 are preferably of segment shape, as best seen in Figure 4, clearance being provided between the slips, as indicated at 58, and the slip support element 24 has a loose fit on the mandrel 12, whereby fluid may pass slowly between the slips and upwardly or downwardly between the slip support and mandrel, while at the same time any sudden movement of mandrel 12 downwardly, such as may take place in the event the fish should wash loose, will cause the slips 32 to engage the wall of the wash-over pipe thereby preventing the fish from falling to the bottom.

The externally enlarged upper end portion 14 of the mandrel is formed with a number of downwardly tapering flat faces 60, positioned for engagement with the inner tapering faces 62 of the slips 32, to expand the slips radially into gripping engagement with the interior of the wash-over pipe, upon downward movement of the mandrel 12 relative to the slip assembly. The flattened external faces of the upper end enlargement of the mandrel constitutes a slip actuator by which the slips may be actuated into gripping engagement with the interior of the wash-over pipe upon downward movement of the mandrel relative to the slip assembly, and whereby the slips may also be disengaged from the wash-over pipe to release the spear when the mandrel is moved upwardly

relative to the slip assembly, or when slips are moved downwardly, as upon downward movement of the wash-over pipe.

The polygonal shape in cross-section of the slip actuator, when in engagement with the inner flat faces of the slips, will cause the slips to tightly grip the interior of the wash-over pipe when expanded, upon rotation of the wash-over pipe 10 so that the mandrel 12 is caused to rotate with the wash-over pipe 10.

In making use of the invention, constructed as described above, the spear assembly is placed in the wash-over pipe 10 at the well surface, and the mandrel 12 is moved longitudinally relative to the slips 32, to set the slips in the wash-over pipe, whereby the spear unit is supported in the wash-over pipe. The pin 30 disposed in the upper portion of the slot 26 as illustrated in Figure 2, depicts the going-in position of the apparatus. The wash-over pipe is then lowered into the well bore, with the apparatus in the condition illustrated in Figure 2, it being understood that the wash-over pipe is connected at its upper end to a tubular operating string of pipe (not shown).

The wash-over pipe 10 is lowered in the well until the lower threaded end 71 of the pin 20 engages the upper end of the stuck pipe or drill collar (not shown), whereupon the wash-over pipe may be rotated to rotate the mandrel 12 to connect the spear unit to the stuck pipe, after which the wash-over pipe may be moved downwardly while fluid is circulated through the operating string and the mandrel 12 and upwardly about the wash-over pipe. It will be apparent that the threaded pin 20 may be provided with a plurality of transversely extending apertures (not shown) communicating from the pin bore and the mandrel 12 to permit fluid circulation from the mandrel and upwardly about the wash pipe, which is old and well known in the art, as is shown in the patent to Howard, 2,502,567, or Le Bus, 2,887,161 and 2,887,162. As soon as the spear has been connected with the fish downward movement of the wash-over pipe causes the slip cage to be moved downwardly relative to the mandrel 12, to move the slips downwardly relative to the slip-engaging faces 60 of the mandrel, so that the slips will be moved to disengaged positions, as seen in Figure 3, to permit the wash-over pipe to be freely rotated and moved downwardly relative to the fish. It will be apparent that an annulus 61 is provided between the mandrel 12 and the wash-over pipe 10.

During downward movement of the wash-over pipe or outer housing 10, the pin 30 will move downwardly in the slot 26, to the position shown in Figure 3. In the event that it should become necessary to remove the wash-over pipe independently of the spear assembly, this may be accomplished by moving the wash-over pipe upwardly, the cylindrical cage 64 being moved upwardly therewith, to move the slip cage upwardly until the pin 30 is opposite the branch slot 28 of the slot 26, whereupon the mandrel may be rotated to move the pin into the branch slot, to hold the slips 32 out of engagement with the actuating faces 60 of the mandrel. With the slips thus held in disengaged position the wash-over pipe may be moved freely upwardly off of the spear.

Should the fish become released in the well bore, during the wash-over operation, and start to fall downwardly in the bore, the mandrel 12 will be suddenly moved downwardly relative to the slip cage 24, to actuate the slips 32 into gripping engagement with the wash-over pipe to connect the fish to the wash-over pipe, whereupon the fish may be moved upwardly with the wash-over pipe and removed from the well.

In removing the equipment from the well with the fish attached to the spear the opening string may be disconnected in the usual manner, one section at a time, as it is withdrawn from the well, until the upper end of the wash-over pipe is reached, whereupon the upper end of the mandrel 12 may be connected to the lower end of a

drill pipe, by means of the internally threaded box 16, and the slips 32 may be disengaged from the wash-over pipe by moving the mandrel upwardly, the pin 30 being then engaged in the branch slot 28, by rotation of the mandrel to hold the slips in released condition. The spear may then be lowered in the wash-over pipe, which is held against downward movement by the customary rotary table mechanism, until the spear is inside of the lowermost section of the wash-over pipe. The spear may then be reengaged with the wash-over pipe by rotating the pin 30 out of the branch slot 28 and the drill pipe disconnected from the spear, whereupon the wash-over pipe may be removed from the well with the fish connected thereto by the spear. In this manner the wash-over pipe and fish may be readily removed from the well without the necessity of carrying out a laborious and time consuming stripping operation which has been customarily employed heretofore with wash-over equipment.

During the washing-over operation the wash-over pipe is lowered relative to the spear until it becomes necessary to add a new section to the upper end of the operating string or drill pipe. The pump pressure at the well surface may then be increased to increase the downward force of the circulating fluid against the restricted flow device 44 to provide expansion thereof outwardly, whereupon the slip cage will be held against upward movement, to permit the wash-over pipe to be slowly moved upwardly without reengaging the slips, whereupon additional drill pipe may be added and the wash-over operation resumed.

For any reason pump pressure cannot be used, or is insufficient to hold the restricted flow device, then the wash-over pipe may be lifted to set the slips and again lowered to release the same and to engage the pin 30 in the branch slot 28, to hold the slips in released position. The wash-over pipe may then be moved upwardly until the kelly is out of the rotary drive mechanism at the top of the well, to permit the addition of additional drill pipe to the letting-in string after which the wash-over operation may be resumed.

By pumping down in the wash-over pipe, pump pressure may be used to hold the flow restricting device against upward movement, to hold the slips released, to prevent wear on the slips while rotating the wash-over pipe during the wash-over operation, but in the event that the fish should become unstuck and start to fall, then the mandrel 12 will move downwardly suddenly to set the slips, so that the fish will be connected to the wash-over pipe.

It will thus be apparent that the hydraulic pressure application on the flow restriction member or fluid packer 46-48 will provide for a static positioning of the slip cage 24 during any upward movement of the wash pipe 10, and thereby preventing engagement of the slips during this movement of the pipe 10. The static positioning of the slip cage by hydraulic pressure is an important feature of this invention in that it prevents engagement of the slips during a vertical reciprocation of the wash pipe in the well bore which may be done many times in an attempt to locate pin and locking mechanisms, such as 28 and 30, or similar locking mechanisms which are well known in fishing tools of this type. It will be apparent that the application of hydraulic pressure to a fluid packer member for static positioning of a slip cage is not limited to a fishing tool of the type depicted in the present invention, but could also be utilized on similar well bore tools, such as pipe cutters, production packers or any place where a tool has to be set and released in an outer tubular string for any particular purpose.

With the use of the hydraulic actuated packer member 46-48, the friction dogs 68 in the present invention are mainly assisting members which can be used in case the packer 46 would be ruptured or the like. Furthermore, the dogs 68 through connection of the buttress

threads 57-59 provide more friction to assist rotation of the cage 24 in the positioning of the pin 30 in the slot 28 for a locked position of the slip cage 24. It will be apparent that while the present invention shows these auxiliary features, the hydraulic fluid packer 46-48 is more efficient in that the pumped pressure at the surface may be increased to increase the displacement of fluid through the tool and the mandrel 12, thereby increasing the efficiency of the packer for holding the slip cage 24 in a position to prevent engagement of the slips 32.

It will thus be seen that the invention, constructed and operated in the manner described above provides wash-over spear mechanism which is of simple design and rugged construction and which may be easily operated by manipulation of the operating string and regulation of the pump pressure, and which is also effective to prevent loss of the fish in the event that the same should become unstuck during the washing-over operation.

The invention has been disclosed herein in connection with a certain specific embodiment of the same, but it will be understood that this is intended by way of illustration only, and that numerous changes can be made in the construction and arrangement of the various parts without departing from the spirit of the invention or the scope of the appended claims.

Having this clearly shown and described the invention, what is claimed as new and desired to secure by Letters Patent is:

1. Wash-over retrieving apparatus comprising a wash-over pipe, a tubular mandrel positioned in the wash-over pipe in a manner to provide an annulus therebetween and for longitudinal movement relative thereto, means for connecting the lower end of the mandrel to the upper end of a pipe in a well bore, a slip cage on and movable longitudinally relative to the mandrel, pipe engaging slips carried by the cage for radial movement relative to the cage into and out of gripping engagement with the surrounding wash-over pipe, means on the mandrel positioned to engage the slips to move the slips into gripping engagement with the wash-over pipe upon longitudinal movement of the mandrel and cage in one direction, and means to disengage the slips to permit the slips to move out of gripping engagement with the wash-over pipe upon longitudinal movement of the mandrel and cage in the other direction, flow restriction means mounted on the cage and operating under the influence of an increase of fluid pressure in the annulus above the flow restriction means for supporting the cage substantially stationary relative to the mandrel during longitudinal movement of the wash-over pipe.
2. In a well tool disposed in a well bore and comprising an outer housing, a tubular mandrel positioned therein for longitudinal movement relative thereto and providing an annulus therebetween, a slip cage provided on and movable longitudinally relative to the mandrel, a plurality of slips mounted on the cage to be movable relative to the cage from a normally retracted position out of engagement with the housing to an expanded position engaging the housing, said mandrel having means for expanding the slips, flow restriction means mounted on the cage and operating under the influence of an increase of fluid pressure in the wash-over pipe above the flow restriction means for supporting the cage substantially stationary to the mandrel during longitudinal movement of the wash-over pipe.
3. In a wash-over retrieving apparatus for use in wells comprising a wash-over pipe, a tubular mandrel positioned in the wash-over pipe for longitudinal movement relative thereto and providing an annulus for fluid flow therebetween, means for connecting the lower end of the mandrel to the upper end of a pipe in a well bore, a slip cage carried by the mandrel for rotatable and longitudinal movement relative thereto, pipe engaging slips carried by the cage and movable relative to the cage from a normally retracted position out of

engagement with the wash-over pipe to an expanded position engaging the wash-over pipe, means on the mandrel for expanding the slips, means on the slips for retracting the slips when in a non-engaging position with the wash-over pipe, fluid lock off means for preventing movement of the slip cage during movement of the wash-over pipe, said fluid lock off means comprising a flow restriction means mounted on the cage and responsive to an increase of fluid pressure in the annulus above the flow restriction means to maintain the cage substantially stationary relative to the mandrel during longitudinal movement of the wash-over pipe.

4. In a wash-over retrieving apparatus for use in wells comprising a wash-over pipe, tubular mandrel positioned in the wash-over pipe for longitudinal movement relative thereto and providing an annulus for fluid flow therebetween, means for connecting the lower end of the mandrel to the upper end of a pipe in a well bore, a slip cage carried by the mandrel for rotatable and longitudinal movement relative thereto, pipe engaging slips carried by the cage and movable relative to the cage from a normally retracted position out of engagement with the wash-over pipe to an expanded position engaging the wash-over pipe, means on the mandrel for expanding the slips, means on the slips for retracting the slips when in a non-engaging position with the wash-over pipe, fluid lock off means for preventing movement of the slip cage during movement of the wash-over pipe, said fluid lock off means comprising a flow restriction means mounted on the cage and responsive to an increase of fluid pressure in the annulus above the flow restriction means to maintain the cage substantially stationary relative to the mandrel during longitudinal movement of the wash-over pipe, auxiliary lock off means for the slip cage comprising a pin provided on the slip cage, a plurality of slots provided on the mandrel for receiving the pin, friction means mounted on the mandrel and engaging the wash-over pipe and movable therewith, said friction means adapted to be engaged with the slip cage upon upward movement of the wash-over pipe for moving the cage pin into a position in the slots whereby rotation of the wash-over pipe will lock the pin in one of the slots and prevent further movement of the slip cage upon continued movement of the wash-over pipe.

5. An apparatus as set forth in claim 4 wherein the friction means are releasable connected with the slip cage.

6. Wash-over retrieving apparatus comprising a wash-over pipe, a tubular mandrel positioned in the wash-over pipe in a manner to provide an annulus therebetween and for longitudinal movement relatively thereto, means for connecting the lower end of the mandrel to the upper end of a pipe in a well bore, a slip cage on and movable longitudinally relative to the mandrel, pipe engaging slips carried by the cage for radial movement relative to the cage into and out of gripping engagement with the surrounding wash-over pipe, means on the mandrel positioned to engage the slips to move the slips into gripping engagement with the wash-over pipe upon longitudinal movement of the mandrel and cage in one direction, and means to disengage the slips 10 to permit the slips to move out of gripping engagement with the wash-over pipe upon longitudinal movement of the mandrel and cage in the other direction, a plurality of independent lock off means for preventing movement of the slip cage during an upward vertical movement of the wash-over pipe, one of said lock off means comprising a flow restriction member mounted on the cage and responsive to an increase of fluid pressure in the annulus above the flow restriction member to maintain the cage substantially stationary relative to 15 the mandrel during longitudinal movement of the wash-over pipe, another of said lock off means comprising a pin provided on the slip cage, a plurality of slots provided on the mandrel for receiving the pin, friction dogs mounted on the mandrel and engaging the wash-over pipe for movement therewith, said friction dogs 20 adapted to be releasably connected with the slip cage for moving the cage pin into a position in the slots whereby rotation of the wash-over pipe will lock the pin in one of the slots and prevent further movement 25 of the slip cage upon continued movement of the wash-over pipe.
